[57] CLAIM

The ornamental designs for a spiral shaped pool float, as shown and described.

DESCRIPTION

FIG. 1 is a perspective view of a spiral shaped pool float having the first embodiment of my new design;

FIG. 2 is a top plan view thereof;

FIG. 3 is a bottom plan view thereof;

FIG. 4 is a side elevation view thereof, the opposite side being a mirror image of that shown;

FIG. 5 is a front elevation view thereof, the rear elevation view being a mirror image of that shown;

FIG. 6 is a perspective view of a spiral shaped pool float having the second embodiment of my new design wherein the spiral shaped pool float has differing colored regions;

FIG. 7 is a top plan view thereof;

FIG. 8 is a bottom plan view thereof;

FIG. 9 is a side elevation view thereof, the opposite side being a mirror image of that shown; and,

FIG. 10 is a front elevation view thereof, the rear elevation view being a mirror image of that shown with the color demarcations of the colored regions reversed.
